(57) **CLAIM**

The ornamental design for a travel organizer, as shown and described.

DESCRIPTION

FIG. 1 is a top, front, right perspective view of a travel organizer showing our new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a top, front, right perspective view of an alternative claimed configuration of a travel organizer showing our new design;

FIG. 9 is a top view thereof;

FIG. 10 is a bottom view thereof;

FIG. 11 is a front view thereof;

FIG. 12 is a rear view thereof;

FIG. 13 is a left side view thereof; and,

FIG. 14 is a right side view thereof.

The travel organizer is shown with a symbolic break in its length width, and height. The appearance of any portion of the article between the break lines forms no part of the claimed design. The even length broken length lines represent stitching and form no part of the claimed design.
